SHOE HANGER

Radley Metzger, New York, N. Y.

Application December 31, 1936, Serial No. 118,521

3 Claims. (Cl. 248—95)

This invention relates to new and useful improvements in a shoe hanger.

The invention has for an object the construction of a shoe hanger which is characterized by 5 a flexible sheet of material adapted to be supported in a vertical plane and supporting shoe receiving pockets, and the provision of stiffening and supporting means upon the top of the sheet of material for supporting the shoe hanger in 10 proper posture.

Still further the invention proposes the provision of a pocket mounted across the top portion of the sheet of material and a stiffening element within the pocket so as to hold the flexible sheet 15 of material uniformly extended.

Still further it is proposed to provide a hook anchored upon the stiffening element and extending upwards to the exterior of the pocket by which the shoe hanger may be supported on a 20 nail, support bar, or the like.

Still further the invention proposes the provision of a staple or other fastening element for attaching the side walls of the pocket with the stiffening element to prevent disengagement of 25 the stiffening element from the pocket.

Still further the invention proposes an arrangement whereby the stiffening element is formed from several sections releasably held on the hook by fastening elements which simultaneously attach 30 the side walls of the pocket with the stiffening element.

For further comprehension of the invention, and of the objects and advantages thereof, reference will be had to the following description 35 and accompanying drawing, and to the appended claims in which the various novel features of the invention are more particularly set forth.

In the accompanying drawing forming a material part of this disclosure:—

40 Fig. 1 is a front elevational view of a shoe hanger constructed according to this invention.

Fig. 2 is a rear elevational view of Fig. 1.

Fig. 3 is a fragmentary sectional view taken on the line 3—3 of Fig. 2.

45 Fig. 4 is a horizontal sectional view taken on the line 4—4 of Fig. 2.

Fig. 5 is a fragmentary view similar to Fig. 2 but illustrating another embodiment of the invention.

50 Fig. 6 is a sectional view taken on the line 6—6 of Fig. 5.

The shoe hanger, according to this invention, comprises a flexible sheet of material 10 adapted to be supported in a vertical plane and provided 55 with shoe receiving pockets 11^a mounted thereon.

An auxiliary pocket 12^a is mounted across the top portion of the sheet of material 10 and encases a stiffening element 13. A hook is anchored to the stiffening element and extends upward to the exterior of the pocket 12.

5 The sheet of material 10 preferably should be fabric or similar material. Binding material 15 is secured to the edges of the sheet 10. The shoe receiving pockets 11^a are formed by horizontal strips of material 11 which are secured to the sheet 10 along spaced vertical lines by vertical stitches 16. These vertical lines of stitches divide off the pockets 11^a. A shoe may be engaged into each pocket through the open top. There are several bands 11 secured in spaced horizontal 15 positions upon one face of the flexible sheet of material 10.

The pocket 12^a is formed by a band of material 12 which is extended across the top portion of the sheet of material 10 and which is secured to the top portion along its top edge and its side edges. Thus the pocket 12^a is open at the bottom. This may be seen in Fig. 3. The stiffening element 13 comprises merely a strip of wood or other similar material arranged within the pocket 13. The 20 hook 14 has a vertical shank portion 14^a which engages through an eyelet 17 in the material of the band 12. It is in this manner that the hook extends to the outside of the pocket. The stem portion 14^a passes through an aperture 18 in the 25 stiffening element 13. There is a washer 19 mounted upon the lower end of the stem 14^a to support the stem in position. The stem 14^a continues into a top hook portion 14^b.

A staple or other fastening element 20 is engaged through one of the walls of the pocket 12^a, preferably the wall formed by the band 12, and engages the stiffening element 13. This staple 20 prevents the stiffening element from moving downwards out through the open mouth of the 30 pocket 12^a when the shoe hanger is not supported by the hook 14. Of course, when it is supported by the hook 14, due to gravity the flexible sheet of material 10 will maintain its position 35 supported on the stiffening element 13.

In Figs. 5 and 6 a modified form of the invention has been disclosed in which provision is made for removing the stiffening element from the pocket 12^a when desired. According to this form of the invention there is a stiffening element 13 formed by adjacent stiffening element sections 13^a which have a passage 18^a through which the shank portion 14^a of the supporting hook may pass. There is a washer 19^a and 19^b fixedly mounted on the stem portion 14^a and engaging the top and bottom 50 55

faces of the stiffening element 13' for preventing the stiffening element from sliding on the shank 14.

The sections 13^a are releasably held together by 5 fastening elements mounted upon the walls of the pocket 12^a and cooperative with each other through openings in the stiffening element. These fastening elements 28 comprise stud sections 23 mounted on one of the walls of the pocket 10 and engageable through aligned openings 24 in the sections 13^a. These stud elements are cooperative with complementary socket elements 23^a mounted on the other wall of the pocket 12^a. When these fastening elements engage each other 15 the sections 13^a are held together, and furthermore the stiffening element is held within the socket 12^a against accidental displacement. In other respects this form of the invention is similar to the previous form and similar parts may be 20 recognized by the corresponding reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I 30 claim as new, and desire to secure by United States Letters Patent is:—

1. In a device of the class described, a flexible body, a flexible strip of material attached by three of its sides across the top of said body with its 35 bottom side free forming a pocket having an open bottom side, a hanger for supporting said body and comprising a stiffening element engageable into said pocket through said open bottom and a hook element extending from said pocket through

an opening in the top thereof, and means for releasably holding said element against accidental displacement and so that it may be removed from said pocket when desired while permitting said body to be easily folded or laundered.

2. In a device of the class described, a flexible body, a flexible strip of material attached by three of its sides across the top of said body with its bottom side free forming a pocket having an open bottom side, a hanger for supporting said body and comprising a stiffening element engageable into said pocket through said open bottom and a hook element extending from said pocket through an opening in the top thereof, and means for releasably holding said element against accidental 15 displacement and so that it may be removed from said pocket when desired while permitting said body to be easily folded or laundered, comprising a fastening element engaging through one of the walls of said pocket and engaging said stiffening 20 element.

3. In a device of the class described, a flexible body, a flexible strip of material attached by three of its sides across the top of said body with its bottom side free forming a pocket having an open 25 bottom side, a hanger for supporting said body and comprising a stiffening element engageable into said pocket through said open bottom and a hook element extending from said pocket through an opening in the top thereof, and means for 30 releasably holding said element against accidental displacement and so that it may be removed from said pocket when desired permitting said body to be easily folded or laundered, comprising shank elements mounted upon one of the walls of said 35 pocket and extending through passages in the stiffening element and cooperative with pocket elements mounted on the other wall of the pocket.

RADLEY METZGER.
